Patented Oct. 6, 1914.

UNITED STATES PATENT OFFICE.

HENRY S. GRAYBILL, OF READING, PENNSYLVANIA.

FLUSH-TANK.

1,112,789.

Specification of Letters Patent.

Patented Oct. 6, 1914.

Application filed August 17, 1911. Serial No. 644,612.

To all whom it may concern:

Be it known that I, HENRY S. GRAYBILL, a citizen of the United States, and a resident of the city of Reading, in the county 5 of Berks and State of Pennsylvania, have invented certain new and useful Improvements in Flush-Tanks, of which the following is a specification.

My invention relates particularly to flush-10 tanks for water closets or the like and a main object of my invention is to provide a valveless mechanism for controlling the discharge.

To this end my invention consists in employing a discharging siphon in connection with means for providing a water-sealed air-space in the reservoir for controlling access of this stored liquid to the short end of the siphon, as fully described in connection with 15 the accompanying drawings; the novel features of the invention being clearly pointed out in the claim.

Figure 1 shows a preferred application of my invention, and Fig. 2 indicates a slightly 20 modified construction embodying the same.

As shown in the drawing, 1 represents a water tank, such as is commonly used in water closets and the like, the automatic filling of which may be effected in well 25 known manner, as by a float operating an inlet valve not shown. Through the bottom 2 of this tank, as illustrated in Fig. 1, depends an air-box extension 3 of the tank or reservoir, said box fitting snugly in an opening 30 in said bottom, and projecting above and below said bottom as shown. This box is preferably cylindrical in shape and is formed with flanges 5 to secure it to the bottom 2, and insure a water tight junction. 35 In this box 3 is mounted a reversely bent outlet pipe forming a siphon, one branch 6 thereof ending close to the bottom 7 of said box, and the other branch 8 passing through said bottom and running to the 40 closet to be flushed. Within the tank is hinged, at 10, a water-sealing cup 9 which is adapted to loosely cover the inner end 4 of the box 3, and to rest loosely on the bottom 2. A float end 11 is formed on said 45 cup 9, opposite the hinge 10, which tends to tilt said cup by raising its free end when the tank is filled with water. Any means to hold said cup in lowered position during the filling and holding of the water in the 50 tank, may be employed, and I have indicated a lever 12, pivoted intermediately of

its length at 13, and having a catch end 14 adapted to engage the float end 11. An inward movement of the upper end 15 of said lever 12 will release the cup 9 from 55 the catch 14 and permit the cup to rise to the dotted-line position indicated, which movement of the lever may be effected by a chain or rod connection to the same and run to a convenient place for the operator. 60

The operation is as follows: The tank 1 being empty, and the cup 9 being held in lowered position as shown, water is turned into the tank by the usual float operated valve or any other means. The water rising in the tank passes under the loosely fitting cup 9, over the top of the extension 4 of the box 3, and rises in the latter until it enters the short arm 6 of the siphon outlet tube. When the short arm of said tube is 65 closed by the rising water, the air in said box under the cup 9, is confined, and presses equally upon the water lying in the bottom of said box and upon the surface of the water surrounding the extension 4 under the 70 cup; so that any additional supply of water to the tank will raise the level in the short arm 6 of the siphon a distance corresponding with the rise in the tank. The length of the short arm 6 thus determines the capacity 75 of the tank before a flushing discharge is made. When a discharge is desired the lever 12 is operated to release the cup 9, the float end of which then rises, releasing the air under it and in the box 3, and permitting the water to fall by gravity into the box and to discharge through the outlet tube 8. As the cap falls with the fall of water in the tank, it again covers the extension 4, and the further discharge of wa- 80 ter from the tank overflows the top of the upward box extension 4, which forms the short arm of a siphon, into the box 3, which forms the long arm thereof, and is then delivered through the discharge siphon, thus 85 emptying the tank. When the cup 9 reaches its lowest position the lever catch 14 automatically engages it, so as to permit of refilling as before. When automatic intermittent flushing is desired a sufficient flow 90 of water to the tank may be provided for to cause the increased head of water in the tank to start the siphon action without raising the cup 9.

The slight modification in construction indicated in Fig. 2, involves no change in 95 the operation described, the air box 3^a be-

ing merely set above the bottom of the reservoir and inclosing only the short leg 6 of the discharging siphon, while the sealing cup is correspondingly deepened and the 5 head of water maintained above the air box reduced; and the tilting of the cup serving in like manner to release the confined air.

It will be understood that other modifications may be readily made without departing from the essential features of the 10 invention as defined in the claim.

I have found in practice that an air outlet hole 16 in the arm 6, aids the escape of excess air under the cup and in the box during 15 the first filling stage, but this is not essential.

It will be readily seen that my improvement provides not only for an inexpensive construction and simple operation, but that 20 the entire elimination of valve elements

avoids much annoyance and expense of maintenance.

What I claim is:—

In a flushing apparatus the combination with a reservoir having an open-top air 25 chamber therein, of a discharging siphon having its shorter branch arranged in communication with the lower portion of said chamber, a hinged inverted float cup arranged to loosely cover said chamber, and 30 operating means comprising a locking device for retaining or releasing said float cup, substantially as set forth.

In testimony whereof, I affix my signature, in the presence of two witnesses.

HENRY S. GRAYBILL.
